BRAKE

Filed Feb. 8, 1926

FIG. 2.

FIG. 3

Fig. 1.

INVENTOR

UNITED STATES PATENT OFFICE.

MONTGOMERY W. McCONKEY, OF WILMETTE, ILLINOIS, ASSIGNOR TO BENDIX BRAKE COMPANY, OF CHICAGO, ILLINOIS, A CORPORATION OF ILLINOIS.

BRAKE.

Application filed February 8, 1926. Serial No. 86,708.

This invention relates to brakes, and is illustrated as embodied in a well-known type of three-shoe internal expanding automobile brake. While the invention is not necessarily limited to this type of brake, an important object is to increase the holding power of such a brake in reverse by introducing an increased "servo" or "self-energizing" action in reverse.

In whatever type of brake the invention may be embodied, important features of novelty relate to novel power-multiplying means, illustrated as a linkage including a toggle, through which an auxiliary servo shoe acts to apply another shoe, the servo shoe preferably being arranged at the anchored end of the shoe which it applies, and if desired overlapping said anchored end.

When embodied in the illustrated type of brake, this gives two servo shoes, one most effective when the car is moving forward and the other in reverse, but both acting on the anchored shoe. The first of these servo shoes is illustrated as connected to the unanchored end of the anchored shoe by a pivot or the like, while the other acts on means, such as the above-described toggle, which is connected to the pivot.

Other features of the invention relate to a novel arrangement of release springs and a stop to determine the positions of the parts when the brake is released, and to other novel combinations of parts and desirable particular constructions which will be apparent from the following description of the illustrative embodiment shown in the accompanying drawing, in which:

Fig. 1 is a vertical section through the brake, just inside the head of the drum, showing the shoes in side elevation;

Fig. 2 is a section on the line 2—2 of Fig. 1, showing in side elevation the overlapping ends of two of the shoes;

Fig. 3 is a section, on the line 3—3 of Fig. 1, through the overlapping ends shown in Fig. 2; and

Fig. 4 is a section on the line 4—4 of Fig. 1, showing the connection of the linkage to the shoe.

The illustrated brake includes a drum 10, at the open side of which is a support such as a backing plate 12, and within which is the friction means of the brake. The illustrated friction means includes a friction device comprising primary and secondary

shoes 14 and 16, connected by means such as a floating pivot 18 and anchored by pivoting the end of shoe 16 on an anchor 20 carried by the backing plate 12, together with an auxiliary shoe 22.

Shoes 14 and 22 may be T-shaped in cross-section, while shoe 16 may be generally channel-section to provide spaced stiffening flanges 24 straddling, at the opposite ends of the shoe, the ends of shoes 14 and 22. Pivot 18 directly connects the left ends (Fig. 1) of flanges 24 to the straddled end of shoe 14. Pivot or anchor 20, for the right-hand ends of flanges 24, passed through a relatively large opening 26 in the stiffening web of shoe 22. Shoes 14 and 22 are preferably identical and interchangeable, and the opening 26 of shoe 14 may be bridged by a pin 28 connected to one end of a spring 30 connected at its other end to the backing plate 12.

The brake may be applied by means such as a double cam 34, which forces toward the drum, against the resistance of a return spring 36, shoes 22 and 14. When the car is moving forward, at which time the drum in Fig. 1 is turning counter-clockwise, shoe 14 turns with the drum when applied and acts as a servo shoe on connection 18 to force shoe 16 against the drum against the resistance of an auxiliary return spring 38. The free ends of shoes 14 and 22 are shown confined laterally by a plate 40 carried by posts 42 passing through openings 44 in the shoes and carried by the backing plate 12.

According to an important feature of the present invention, auxiliary shoe 22 or its equivalent also acts as a servo shoe, especially when drum 10 in Fig. 1 is turning clockwise, i. e. when the vehicle is moving backward. In thus acting as a servo shoe, I prefer that it act on the unanchored end of shoe 16, for example on pivot 18, by novel power-multiplying means illustrated as a toggle including links 50 and 52 on which the servo shoe acts through a link 54.

When thus arranged, links 52 may be pivoted on pivot 18 on opposite sides of shoe 14 and between the flanges 24 of shoe 16, while links 50 are mounted on a pivot 56 carried by the backing plate 12. As the toggle opens to the left in Fig. 1, it will be seen that the auxiliary return spring 38 tends to break the toggle, whereas when shoe 22 turns clockwise with the drum it thrusts

link 54 in a direction tending to straighten the toggle and force the unanchored ends of shoe 16 toward the drum. Link 54 is shown forked at its right-hand end (Fig. 1), to project between flanges 24 of shoe 16 and to straddle the end of shoe 22, to which shoe it is connected by a pivot pin 58. Pin 58 projects through relatively large openings 60 in flanges 24, and has an enlarged head 62 slidably engaging the backing plate 12.

When the brake is released, the idle positions of link 54 and of the lower end of shoe 22 are determined by a suitable stop 64, shown as an adjustable eccentric carried by plate 12, which fits into the angle between the link and the shoe, and against which they are held by a spring 66. Spring 66 is connected at one end to the backing plate 12 and at its other end to link 54, and is inclined at such an angle as to urge both link 54 and shoe 22 into engagement with stop 64. Stop 64 thus determines the position of link 54 lengthwise, spring 38 being made too light to act through the toggle to force shoe 22 away from stop 54. However, spring 38 does break the toggle to swing shoe 16 away from the drum, as far as permitted by the seating of stop 64 in the angle between link 54 and shoe 22. Thus stop 64 acts through the toggle to determine the idle position of shoe 16.

It will be seen that, in the illustrated arrangement, both of the shoes 14 and 22 are servo shoes tending to apply shoe 16, shoe 14 being the more effective of the two when the vehicle is moving forward, and shoe 22 being the more effective when the vehicle is moving backward. It is not my intention, however, to limit the scope of the invention to the particular brake illustrated, or otherwise than by the terms of the appended claims.

I claim:

1. A brake comprising, in combination, a plurality of at least three shoes arranged end to end, and applying means connecting the same end of the intermediate shoe to the two shoes at its opposite ends.

2. A brake comprising, in combination, a pair of pivotally connected shoes, and a third shoe connected to the pivotally connected ends of said pair of shoes.

3. A brake comprising, in combination, a drum, a pair of shoes, an anchor for one of the shoes at the end adjacent the other shoe, means acting on the opposite end of said other shoe to force it against the drum, and means operated by said other shoe for forcing the unanchored end of the anchored shoe against the drum.

4. A brake comprising, in combination, a drum, a pair of shoes, an anchor for one of the shoes at the end adjacent the other shoe, means acting on the opposite end of said other shoe to force it against the drum, and

a linkage operated by said other shoe for forcing the unanchored end of the anchored shoe against the drum.

5. A brake comprising, in combination, a pair of shoes 14 and 16 arranged end to end and having a connection 18 between their adjacent ends, applying means acting on the unconnected end of one of the shoes, and auxiliary applying means acting on the connection between the shoes. 75

6. A brake comprising, in combination, a pair of shoes arranged end to end and connected at their adjacent ends, applying means acting on the unconnected end of one of the shoes, and auxiliary applying means 80 acting on the connected ends of the shoes.

7. A brake comprising, in combination, three shoes arranged end to end, and applying means through which both end shoes act on the same end of the center shoe. 85

8. A brake comprising, in combination, a drum, a shoe engageable with the drum, a toggle fixed at one end and connected at its other end to force the shoe against the drum, and an auxiliary shoe acting on the knuckle 90 of said toggle to force the first shoe against the drum.

9. A brake comprising, in combination, a drum, a support, a shoe engageable with the drum, a toggle pivoted at one end on the support for forcing said shoe against the drum, and an auxiliary shoe acting on said toggle to force the first shoe against the drum. 95

10. A brake comprising, in combination, a drum, a shoe, a device for forcing said shoe against the drum, an auxiliary shoe engageable with the same zone of the drum as the first shoe and operating said device and auxiliary means for forcing the first shoe against the drum independently of said device. 100

11. A brake comprising, in combination, a drum, a shoe engageable with the drum, a toggle for forcing said shoe against the drum, an auxiliary shoe engageable with the drum, and a link connected at one end to the auxiliary shoe and at the other end to the toggle. 110

12. A brake comprising, in combination, a drum, a shoe anchored at one end and engageable with the drum, and an auxiliary shoe overlapping the anchored end of said first shoe and acting on its unanchored end to force it against the drum. 115

13. A brake comprising, in combination, a drum, a shoe anchored at one end and engageable with the drum, and an auxiliary shoe overlapping the anchored end of said first shoe and linked to its unanchored end to force it against the drum. 120

14. A brake comprising, in combination, a drum, a shoe anchored at one end and engageable with the drum, and a pair of shoes 135 arranged at opposite ends of the anchored

shoe and both of which act on the unanchored end of the anchored shoe to force it against the drum.

15. A brake comprising, in combination, a drum, a shoe anchored at one end and engageable with the drum, and a pair of shoes arranged at opposite ends of the anchored shoe and both of which are connected to the unanchored end of the anchored shoe to force it against the drum.

16. A brake comprising, in combination, a drum, a shoe anchored at one end and engageable with the drum, and a pair of shoes overlapping opposite ends of the anchored shoe and both of which act on the unanchored end of the anchored shoe to force it against the drum.

17. A brake comprising, in combination, a first shoe anchored at one end, a second shoe at the unanchored end of the first shoe, a connection between said shoes, a third shoe at the anchored end of the first shoe, and means through which the third shoe acts on said connection to apply the first shoe.

25 18. A brake comprising, in combination, a first shoe, a second shoe at one end of the first shoe, a connection between said shoes, a third shoe at the other end of the first shoe, and means through which the third shoe acts on said connection to apply the first shoe.

19. A brake comprising, in combination, a drum, a pair of shoes engageable with the drum, a device through which one of said shoes forces the other against the drum, and an auxiliary shoe also acting on said device.

20. A brake comprising, in combination, a drum, a pair of shoes engageable with the drum, a pivot connecting the shoes, an auxiliary shoe, and brake-applying means operated by the auxiliary shoe and acting on the pivot.

21. A brake comprising, in combination, a drum, a pair of shoes engageable with the drum, a pivot connecting the shoes, an auxiliary shoe, and a linkage connecting the auxiliary shoe and said pivot.

22. A brake comprising, in combination,

a drum, a pair of shoes engageable with the drum and one of which is anchored at the end adjacent the other, one of the shoes having spaced flanges straddling the end of the other, a pivot at the end of the unanchored shoe, a link having arms projecting between the two shoes and straddling the inner shoe and straddled by said spaced flanges, and actuating means operated by said link to force the anchored shoe against the drum.

23. A brake comprising, in combination, a drum, a friction device anchored at one end and engageable with the drum and including connected shoes, an auxiliary servo shoe at the anchored end of the friction device, brake-applying means for forcing against the drum the auxiliary shoe and the unanchored end of the friction device, and auxiliary power-multiplying connections operated by the auxiliary shoe for forcing said friction device against the drum.

24. A brake comprising, in combination, a drum, a friction device anchored at one end and engageable with the drum, an auxiliary servo shoe at the anchored end of the friction device, brake-applying means for forcing against the drum the auxiliary shoe and the unanchored end of the friction device, and auxiliary power-multiplying connections between the auxiliary shoe and a part of the friction device between its ends.

25. A brake comprising, in combination, a drum, an anchored shoe, a brake-applying toggle acting on said shoe, a spring tending to break the toggle to urge the shoe away from the drum, an auxiliary shoe acting on the toggle in a manner tending to straighten it to force the anchored shoe against the drum, a stop arranged to determine the position of the auxiliary shoe when the brake is released and also arranged to determine the position of the toggle and through the toggle of the anchored shoe when the brake is released, and means yieldingly urging the auxiliary shoe toward an idle position determined at least in part by the stop.

In testimony whereof, I have hereunto signed my name.

MONTGOMERY W. McCONKEY.

DISCLAIMER

1,639,142.—*Montgomery W. McConkey*, Wilmette, Ill. BRAKE. Patent dated August 16, 1927. Disclaimer filed September 8, 1930, by the patentee and the assignee, *Bendix Brake Company*.

Hereby jointly and severally disclaim from the scope of claims 2, 5, 6, 10, 18, 19, 20, and 21 of said patent all brake structures except those comprising at least three brake shoes of which an intermediate or secondary shoe is anchored to a fixed part.
